UNITED STATES PATENT OFFICE.

HOWARD GEORGE WALKER, OF BERWYN, AND ALBERT THOMAS MARCH, OF CHICAGO,
ILLINOIS, ASSIGNORS TO WESTERN ELECTRIC COMPANY, INCORPORATED, OF NEW
YORK, N. Y., A CORPORATION OF NEW YORK.

METHOD AND APPARATUS FOR PRODUCING FIBROUS ARTICLES.

Application filed February 27, 1923. Serial No. 621,530.

This invention relates to a method of and apparatus for producing fibrous articles, and more particularly to a method of and apparatus for coating cores.

One object of the invention is to produce a core having a coating of pulp thereon which is attached to the core solely by an intermingling of the fibers thereof and without the use of any adhesive substance.

Another object of the invention is to produce a fibrous sheet consisting solely of intermingled pulp fibers.

Briefly, the method consists in depositing pulpous material upon a foraminous member, removing moisture from the deposited material, and applying pressure to the deposited material to release it from the foraminous member. When a core is being coated the pulpous material is deposited upon the core as well as upon the foraminous member and the material after being released from the foraminous member is formed around the core to constitute a homogeneous coating therefor.

The present method may be employed to advantage for insulating electrical conductors, but it is to be understood that it is not limited to this purpose but only in so far as is defined by the appended claims. Where the method is used for insulating electrical conductors, manila, wood, rag, cotton, esparto, jute, hemp and asbestos pulps may be employed as the coating material, but other materials than those specified may be used without departing from the spirit and scope of the present invention which contemplates in its broadest aspect the coating of any core with any pulp.

The drawings illustrate an apparatus by which the method may be practiced, the apparatus being especially designed for coating a core in strand form or for making a fibrous sheet, but it is to be understood that other apparatus may be devised for coating cores in other forms without departing from the spirit and scope of the invention.

The word "pulp" as used in the specification and claims is to be understood as defining and including any cohering fibrous mass whether suspended in a liquid, moist, or substantially dry.

In the accompanying drawings:

Fig. 1 is a side elevation of a preferred apparatus for performing the process;

Fig. 2 is a top plan view of the apparatus shown in Fig. 1, parts being omitted therefrom for the sake of clearness;

Fig. 3 is a fragmentary side elevation, in section, of such apparatus showing the method in which the pulpous material is deposited upon the rotatable foraminous member and on the core;

Fig. 4 is a fragmentary longitudinal view, in section, of the rotatable member and its associated mounting;

Figs. 5 and 6 are enlarged views showing the form of the pulp coating on the core as it is delivered from the carrier and the squeezing rolls respectively;

Figs. 7 and 8 are enlarged views showing the form of the pulp coating on the core during the forming operation and after the forming operation is completed respectively, and

Fig. 9 is a fragmentary side elevation showing a modification of the rotatable foraminous member.

The steps of the method will be readily understood from a detailed description of the apparatus by which the method can be practiced. Referring to the drawings in detail in which like reference numerals designate similar parts throughout the several views, a core to be coated is fed from a supply roll 10 over an idler roll 11, and then around a drum 12 which is partially submerged in a fluid containing pulp within a semi-circular trough 13. The drum 12 may be of any suitable type, preferably having one end open while the other end is closed by a sheet metal side 14. The drum is rotated around a fixed tubular axle 18 by means of a pulley 19 attached by means of a set screw 20 or otherwise to a bearing member 21 which carries by a plurality of arms 22 a peripheral portion 23. Attached to the portion 23 at opposite sides of the drum are formed members 24 and 25 which extend toward the center of the drum and leave an opening 16 therebetween, which opening is covered by a strip of fine wire mesh or other suitable foraminous material 17. Attached to a right-hand peripheral portion 54 similar to a portion 23 and therethrough to the member 25 are a plurality of radial arms 26 similar in character to arms 22 and which terminate in a bearing ring 27 rotating upon the tubular

axle 18 for supporting the associated end of the drum 12.

- The left-hand end of the tank is closed, where the tubular axle enters, by means of 5 a stuffing box of any usual structure which may comprise a gland member 28 of any suitable packing material, held in place by a threaded nut 29, engaging the threaded extension 30 of the tank. The right hand 10 end of the drum is open as indicated, and an opening corresponding with a portion of such opening, is provided in the right hand side of the tank. Attached to the edge of the right hand end of the tank which is in 15 contact with the moving peripheral portion 23 of the drum is a partial water seal 32 of canvas or a similar material, which is bent at right angles and caused to rotatably engage the periphery of the portion 54. A 20 hoop member 34 of any suitable material and clamped together in any desirable manner at the top of the apparatus, as by a suitable bolt and nut clamp 35, serve to maintain the canvas 32 in engagement with the portion 25 54 as the drum rotates and thus substantially prevents the escape of liquid from the tank into a receptacle 38 attached at the right hand end of the drum. A collar 39 attached to the tubular axle 18 positions the 30 bearing member 27 on the axle. The axle 18 is supported in a suitable manner, such as by the supports 40 and 41, from a framework 42, which also serves to support all of the other parts of the apparatus.
- 35 Extending through the hollow shaft 18 are conduits 44 and 45 which are bent at right angles, extend through suitable bushing members in the axle, and terminate in open chambers or compartments 47 and 48 respectively. The peripheral portion 23 of the drum in rotating remains in contact with the edges of the walls of these chambers or compartments, and as the drum rotates, the openings in the bottoms of compartments 45 formed in the drum by the radially disposed walls 49, cooperating with the members 24 and 25, are placed successively in engagement with the open ends of the compartments 47 and 48 through the openings 50 in the drum compartments. The compartments 47 and 48 are suitably supported from the stationary axle 18 by means of a frame work 51.
- 55 Extending from the right into the receptacle 38 attached to the right-hand side of the tank 13 is a conduit 52 which terminates in an adjustable inlet pipe 53. The pipe 53 may be rotated around the conduit 52 so as to maintain the height of the fluid within the drum 12 and the receptacle 38 at the level indicated by a dotted line A. The fluid containing pulp outside of the drum 12 and within the tank 13 is maintained at a level indicated by a dotted line B. These 60 65 levels are maintained due to the action of

the conduit 52 and its adjustable inlet 53, as well as by supplying additional pulp fluid through a pipe 54', connected with any suitable supply tank (not shown), and by an adjustable discharge pipe 55. A continuous circulation of the pulp mixture is maintained by feeding the pulp mixture from the pipe 54' into the left-hand end of the tank 13 and out of the tank through the pipe 55 into a receiving tank (not shown), from which it is pumped into a tank (not shown) associated with the supply pipe 54'. As the drum 12 revolves in the tank, due to the difference in levels of the fluid in the tank and in the drum and associated receptacle 38, the fluid will pass through the fine wire mesh 17 in the drum, straining the pulpy material onto the surface of such mesh. It will be noted that by adjusting the height of pipe 55 as well as adjusting the position of pipe 53, the difference in levels A and B or the effective head of the supply may be varied as desired.

Attention is called to the fact that the idler roll 11 is so placed from the periphery of the drum 12 that the core is held out of contact with that section of the foraminous portion of the drum which is near the surface of the fluid in the tank, whereby pulp is strained onto said section of the foraminous strip 17 before the strand is brought into contact therewith. The first deposit of pulp on the foraminous portion is indicated by the letter C (Fig. 3). As the drum revolves in the tank, an additional amount of pulpy material will be deposited upon the core and also upon the foraminous portion of the drum, forming a thicker coating, indicated by the letter D (Fig. 3). The drum 12 is rotated in the direction indicated by the arrow by means of a belt driven from a source of power and cooperating with the pulley 19, and the pulp on the foraminous member 17 after it emerges from the level of the fluid is subjected to suction applied from any suitable source through the conduit 44 to the chamber 47. Thus as the core and the deposited material reach a point in line with the chamber 47, moisture is extracted from said pulp by means of the suction arrangement. Although the suction pipe is shown as being applied to only one or possibly two of the drum compartments, it is to be understood that the chamber 47 may be made of such dimensions as to include a greater number of the drum compartments. After a considerable portion of the moisture has been removed from the pulp, the drum reaches a point in line with the chamber 48 which is subjected to pressure, such as compressed air, supplied from a suitable source through the conduit 45 and blowing against the under side of the pulp as it is secured to the foraminous strip 17 on the drum 12.

This pressure tends to release the pulpoous material from the foraminous member and as the core and the associated pulp leave the drum, they assume a shape substantially as shown in Fig. 5. Thereafter the core and the deposited pulp pass through a pair of squeezing rolls 56 and 57, the latter of which is driven by a belt 58 connected to any suitable source of power. The rolls 56 and 57 are carried by a suitable bracket 59 secured to a framework 60 supported upon a common framework 42. The rolls 56 and 57 are forced together by any suitable tension means which is adjustable to exert the proper pressure upon the core and the pulp as they pass between the rolls, this process serving to mat the pulpoous material and secure it to the core to such an extent that the core and the pulp as they leave the rolls assume the form shown in Fig. 6. From the squeeze rolls the core with its ribbon pulp coating is drawn through a former, designated generally by the character 61, which wraps the projecting edges of the ribbon around the core and around each other, the appearance of the coating after it is first acted on by the former and after the forming action is completed being shown in Figs. 7 and 8 respectively. The former causes a thorough intermingling of the pulp fibres and shapes the coating so that it embraces the core and conforms to the shape thereof. This step of the process forms the coating into a mass so homogeneous that upon cutting the core and coating, the latter will not fray or ravel and will not become easily detached from the core.

The former 61 is illustrated as being of the same type as that fully shown and described in a co-pending application of Walker and March, Serial No. 547,923, filed March 29, 1922. Reference is made to such application for a full disclosure thereof.

The former consists essentially of two plates 62 and 63 which wrap the projecting edges of the pulp ribbon around each other and around the core in much the same manner as though the core and the pulp ribbon were rolled on a table top with the palm of the hand.

The core with its formed coating is then drawn from the former and subjected to a mechanism for thoroughly drying out the coating. The means shown for performing this step in the process are a pair of wide hollow drums 64 and 65, heated internally and having a plurality of grooves 66 formed thereon (Fig. 2), which receive the core, guides (not shown) being provided for directing the core over first one of the drums and then over the other drum until it has traversed all of the grooves on both drums, after which it is stored on a receiving drum 67. Drums 64, 65, and 67 are revolably mounted in suitable bearings carried by vertical standards supported by the framework 42. The drum 64 is driven by a belt 68 connecting with any suitable source of power and in turn drives the drum 67 through the medium of a belt 69.

In case the machine disclosed is to be employed for making a fibrous sheet as in the manufacture of paper, the supply roll 10, the idler roll 11, and the core carried thereby and the apparatus shown for squeezing the pulp on the core and forming the coating of pulp around the core, as well as for drying the coated core after it has been passed through the former 61 may be omitted. The foraminous strip 17 of the drum 12 determines the width of the sheet to be manufactured and may be made of any suitable width. In this case, after a considerable portion of the moisture has been removed from the sheet by the suction means applied through the chamber 47, the pressure applied through the chamber 48 tends to release the pulp from the foraminous member 17 so that it may be lifted therefrom and passed over the usual drying and calendar rolls employed in the manufacture of sheets or strips of paper in the ordinary manner.

In Fig. 9 a modification of the drum 12 and associated apparatus is shown wherein the suction effect utilized for straining the fluid through the foraminous member 17 may be supplemented by additional positive suction means operating through a conduit 70 leading through the hollow shaft 18 and extending at right angles thereto into a chamber 71 which is located beneath the level of the fluid outside of the drum. In this manner it is possible to cause the deposit of pulp in greater quantities upon the foraminous member 17 and in some cases it may be desirable to have the chamber 71 extended to cover a plurality of the drum chambers instead of being applied to only one chamber as shown in the drawing.

Although it has been stated that one of the objects of the invention is to apply a coating of pulp to a core without the use of any adhesive substance, the process herein disclosed may be used with a pulp mixture containing a sizing substance, or the pulp may be deposited on a core which has been previously treated with an adhesive agent, without departing from the spirit and scope of the present invention.

What is claimed is:

1. A method of coating a core in strand form with pulp, which consists in depositing wet pulpoous material on a foraminous member, positioning the core adjacent said deposited material, depositing additional wet, pulpoous material on the core and on said foraminous member, removing the core and all of the pulpoous material from the foraminous member and then forming the

- material on the core to constitute a coating conforming with the shape of the core.
2. A method of coating a core in strand form with pulp, which consists in depositing wet, pulpoous material on a foraminous member, positioning the core adjacent said deposited material, depositing additional wet, pulpoous material on said foraminous member, removing the core and all of the pulpoous material from the foraminous member and then forming the material on the core to constitute a coating conforming with the shape of the core.
3. A method of coating a core in strand form with pulp, which consists in depositing wet, pulpoous material on a foraminous member, positioning the core adjacent said deposited material, depositing additional wet pulpoous material on the core, removing the core and all of the pulpoous material from the foraminous member and then forming the material on the core to constitute a coating conforming with the shape of the core.
4. A method of coating a core in strand form with pulp, which consists in depositing a ribbon of wet, pulpoous material on a foraminous member, positioning the core adjacent said deposited ribbon, depositing additional wet pulpoous material on the ribbon, removing the core and all of the deposited material from the foraminous member and then forming the material on the core to constitute a coating conforming with the shape of the core.
5. A method of coating a core in strand form with pulp, which consists in depositing a ribbon of wet, pulpoous material on a foraminous member, positioning the core adjacent said deposited ribbon, depositing additional wet, pulpoous material on the core, removing the core and all of the deposited material from the foraminous member and then forming the material on the core to constitute a coating conforming with the shape of the core.
6. A method of coating a core in strand form with pulp, which consists in depositing a ribbon of wet, pulpoous material on a foraminous member, positioning the core adjacent said ribbon, depositing additional wet, pulpoous material on the core and on the ribbon, removing the core and all of the deposited material from the foraminous member and then forming the material on the core to constitute a coating conforming with the shape of the core.
7. A method of coating a core in strand form with pulp, which consists in straining fluid containing pulpoous material through a foraminous member to thereby deposit pulpoous material thereon, causing relative movement between the core and the foraminous member to adjacently position the core and the deposited material, depositing additional pulpoous material on the forami-
- nous member, causing relative movement between the foraminous member and the core whereby all of the said deposited material is retained on the core and then forming the material on the core to constitute a coating conforming with the shape of the core.
8. A method of coating a core in strand form with pulp, which consists in depositing wet, pulpoous material on a foraminous member, positioning the core adjacent said deposited material, depositing additional wet pulpoous material on the core and on said foraminous member, removing the greater part of the moisture from said pulpoous material, removing the core and all of said pulpoous material from the foraminous member, and then forming the pulpoous material around the core to constitute a homogeneous coating therefor conforming with the shape of the core.
9. A method of coating a core in strand form with pulp, which consists in depositing wet, pulpoous material on a foraminous member, positioning the core adjacent said deposited material, depositing additional wet pulpoous material on the core and on said foraminous member, removing the greater part of the moisture from said pulpoous material, removing the core and all of said pulpoous material from the foraminous member, forming the pulpoous material around the core to constitute a homogeneous coating therefor conforming with the shape of the core, and then removing substantially all of the moisture from said coating.
10. A method of coating a core in strand form with pulp, which consists in depositing wet, pulpoous material on a foraminous member, positioning the core adjacent said deposited material, depositing additional wet, pulpoous material on the foraminous member, removing some of the moisture from the deposited material, removing the core and all of the pulpoous material from the foraminous member and then forming the material on the core to constitute a coating conforming with the shape of the core.
11. A method of coating a core in strand form with pulp, which consists in depositing wet, pulpoous material on a foraminous member, positioning the core adjacent said deposited material, depositing additional wet, pulpoous material on the core and on said foraminous member, removing some of the moisture from the pulpoous material, removing the core and all of the pulpoous material from the foraminous member and then forming the material on the core to constitute a coating conforming with the shape of the core.
12. A method of coating a core in strand form with pulp, which consists in depositing wet, pulpoous material on a foraminous member, positioning the core adjacent said deposited material, depositing additional wet,

- 5 pulpous material on the core, removing some of the moisture from the deposited material, removing the core and all of the pulpous material from the foraminous member and then forming the material on the core to constitute a coating conforming with the shape of the core.
13. A method of coating a core in strand form with pulp, which consists in depositing 10 a ribbon of wet, pulpous material on a foraminous member, causing relative movement between the core and the member to adjacently position the core and the ribbon, depositing additional wet, pulpous material 15 on the ribbon, removing the core and all of the deposited material from the foraminous member, and then wrapping the ribbon and the additional deposited material around the core to constitute a homogeneous coating 20 therefor.
14. A method of coating a core in strand form with pulp, which consists in depositing a ribbon of wet, pulpous material on a foraminous member, positioning the core adjacent 25 and parallel with said deposited ribbon, depositing additional ribbon of wet, pulpous material on the core and foraminous member, removing the core and the ribbon of pulpous material from the foraminous member, and 30 then wrapping the ribbon around the core to constitute a homogeneous coating therefor.
15. A method of coating a core with pulp, which consists in depositing wet, pulpous material on a foraminous member, positioning 35 the core adjacent the deposited material, removing the core from the foraminous member, directing a current of air against the deposited material to release it from the foraminous member contemporaneously with 40 the removal of the core therefrom.
16. A method of coating a core with pulp, which consists in depositing wet, pulpous material on a foraminous member, positioning the core adjacent the deposited material, 45 removing the core from the foraminous member, applying pressure to the deposited material to release it from the foraminous member contemporaneously with the removal of the core therefrom.
17. A method of coating a core with pulp, which consists in depositing wet, pulpous material on a foraminous member, positioning the core adjacent the deposited material, removing the core from the foraminous 55 member, directing a current of air through the foraminous member against the deposited material to release it from the foraminous member contemporaneously with the removal of the core therefrom.
18. A method of coating a core with pulp, which consists in depositing wet, pulpous material on a foraminous member, positioning the core adjacent said deposited material, depositing additional wet, pulpous material on the core and on said foraminous 60 member, removing the greater part of the moisture from said pulpous material whereby it is attached to the core, subjecting the under side of the foraminous member to pressure sufficient to dislodge therefrom the 70 pulpous material deposited thereon, and then removing said core and pulpous material from the foraminous member.
19. A method of coating a core with pulp, which consists in depositing wet, pulpous 75 material on a foraminous member, positioning the core adjacent said deposited material, depositing additional wet, pulpous material on the core and on said foraminous member, removing the greater part of the moisture from said pulpous material whereby it is attached to the core, subjecting the under side of the foraminous member to pressure sufficient to dislodge therefrom the 80 pulpous material deposited thereon, removing said 85 core and pulpous material from the foraminous member, and then forming said material on the core to constitute a homogeneous coating therefor.
20. A method of coating a core with 90 pulp, which consists in depositing wet, pulpous material on a foraminous member, positioning the core adjacent said deposited material, depositing additional wet, pulpous 95 material on the core and on said foraminous member, removing the greater part of the moisture from said pulpous material whereby it is attached to the core, subjecting the under side of the foraminous member to air, pressure sufficient to dislodge therefrom the 100 pulpous material deposited thereon, and then removing said core and pulpous material from the foraminous member.
21. A method of coating a core with pulp, which consists in depositing wet, pulpous 105 material on a foraminous member, positioning the core adjacent the deposited material, depositing additional wet pulpous material on the core and on said foraminous member, permitting the free liquid in the pulpous 110 material on the core and on the foraminous member to drain through the said member, subjecting the pulpous material on the core and on the foraminous member to suction 115 to remove the greater part of the moisture from said pulpous material whereby it is attached to the core, then subjecting the pulpous material on the core and on the foraminous member to air pressure to remove the pulpous material from the foraminous 120 member, and then removing the core carrying the pulpous material from the foraminous member.
22. A method of coating a core with pulp, which consists in depositing wet, pulpous 125 material on a foraminous member positioning the core adjacent the deposited material, depositing additional wet, pulpous material on the core and on said foraminous member, permitting the free liquid in the 130 material on the core and on said foraminous member,

- 55 pulpos material on the core and on the foraminous member to drain through the said member, subjecting the pulpos material on the core and on the foraminous member to suction to remove the greater part of the moisture from said pulpos material whereby it is attached to the core, subjecting the pulpos material on the core and on the foraminous member to air pressure to remove the pulpos material from the foraminous member, then removing the core carrying the pulpos material from the foraminous member, and then forming said material on the core to constitute a homogeneous coating therefor.
23. A method of coating a core in strand form with pulp, which consists in depositing pulpos material on a foraminous member, positioning the core adjacent said deposited material, depositing additional pulpos material on the core and on said foraminous member, so treating the pulpos material on the foraminous member that it is attached to the core, subjecting the pulpos material on the foraminous member to pressure sufficient to remove the pulpos material therefrom, removing the core from the foraminous member carrying the pulpos material therewith and then forming the material on the core to constitute a coating conforming with the shape of the core.
24. A method of coating a core in strand form with pulp, which consists in depositing pulpos material on a foraminous member, positioning the core adjacent said deposited material, depositing additional pulpos material on the core and on said foraminous member, so treating the pulpos material on the foraminous member that it is attached to the core, then subjecting the pulpos material on the foraminous member to pressure sufficient to remove the pulpos material therefrom, removing the core from the foraminous member carrying the pulpos material therewith, forming said material on the core to constitute a homogeneous coating therefor conforming with the shape of the core.
25. A method of coating a core in strand form with pulp, which consists in depositing a ribbon of wet, pulpos material on a foraminous member, placing the core adjacent said deposited material, depositing additional wet, pulpos material on the core and on said deposited ribbon, removing the greater part of the moisture from said pulpos material on the core and on the foraminous member whereby it is attached to the core, subjecting the pulpos material on the foraminous member to a pressure sufficient to remove the material from said member, removing the core carrying the pulpos ribbon therewith from the foraminous member and then forming the material on the core to

constitute a coating conforming with the shape of the core.

26. A method of coating a core with pulp, which consists in depositing a ribbon of wet, pulpos material on a foraminous member, placing the core adjacent said deposited material, depositing additional wet, pulpos material on the core and on said deposited ribbon, removing the greater part of the moisture from said pulpos material on the core and on the foraminous member whereby it is attached to the core, subjecting the pulpos material on the foraminous member to a pressure sufficient to remove the material from said member, removing the core carrying the pulpos ribbon therewith from the foraminous member, and then wrapping said ribbon around the core to constitute a homogeneous coating therefor.

27. In a machine for coating a core in strand form, a tank of fluid containing pulp, a rotatable member mounted in said tank, said member having a foraminous portion, means for straining pulp from said fluid onto said foraminous portion, means for drawing said strand around said rotatable member into contact with the deposited material on said foraminous portion, means for removing said pulp and core from said foraminous portion and then forming the material on the core to constitute a coating conforming with the shape of the core.

28. In a machine for coating a core in strand form, a tank of fluid containing pulp, a rotatable member mounted in said tank, said member having a foraminous portion, means for straining pulp from said fluid onto said foraminous portion, means for drawing said strand around said rotatable member into contact with the deposited material on said foraminous portion, and means for removing said pulp and said core from said foraminous portion, said means including means for directing a current of air against the pulp on said foraminous portion to assist in the release of the pulp from the member.

29. In a machine for coating a core in strand form, a tank of fluid containing pulp, a rotatable member mounted in said tank, said member having a foraminous portion, means for straining pulp from said fluid onto said foraminous portion, means for drawing said strand around said rotatable member into contact with the deposited material on said foraminous portion, means cooperating with the foraminous portion for removing some of the moisture from the pulp thereon, means for removing the pulp and the core from the foraminous portion and then forming the material on the core to constitute a coating conforming with the shape of the core.

30. In a machine for coating a core in

- strand form, a tank of fluid containing pulp, a rotatable member mounted in said tank, said member having a foraminous portion, means for straining pulp from said fluid onto said foraminous portion, means for drawing said strand around said rotatable member into contact with the deposited material on said foraminous portion, means co-operating with the foraminous portion for removing a portion of the moisture from said deposited pulp, and means also co-operating with said foraminous portion for removing the said pulp and said core from said foraminous portion and then forming the material on the core to constitute a coating conforming with the shape of the core.
31. In a machine for coating a core in strand form, a tank containing a mixture of liquid and pulp, a rotatable member mounted in said tank, said member having a foraminous portion, means for straining pulp from said liquid onto said foraminous portion, means for drawing said strand around the rotatable member and into contact with the deposited material on the foraminous member, removing the greater part of the moisture from said pulpous material on the core and foraminous portion, and means for removing the pulpous material from the foraminous portion, said means comprising a source of pressure connected with said foraminous portion.
32. In a machine for coating a core in strand form, a tank containing a mixture of liquid and pulp, a rotatable member mounted in said tank, said member having a foraminous portion, means for straining pulp from said liquid onto said foraminous portion, means for drawing said strand around said rotatable member and into contact with the deposited material on said foraminous portion, suction means connected with said foraminous portion for removing the greater part of the moisture from the pulpous material on the foraminous portion and on said core, and pressure means connected with said foraminous portion for removing the pulpous material deposited thereon.
33. A method of coating a core in strand form with pulp, which consists in depositing wet pulpous material on a foraminous member, removing moisture from the deposited pulpous material to form a sheet, passing a current of air through the foraminous member to release the pulpous material from the member, removing the pulpous material from the member, and then forming the said pulpous material on the core to constitute a coating on the core to conform with the shape thereof.
34. A method of coating a core in strand form with pulp, which consists in positioning the core adjacent a foraminous member, causing relative movement between a supply of fluid containing pulp and the foraminous member to deposit wet pulpous material on the member, applying pressure to the pulpous material to release it from the foraminous member, removing the core and pulpous material from the foraminous member, and then forming the pulpous material on the core to constitute a coating thereon conforming with the shape of the core.
35. A method of coating a core in strand form with pulp, which consists in positioning the core adjacent a foraminous member, causing relative movement between a supply of fluid containing pulp and the foraminous member to deposit wet pulpous material on the member, passing a current of air through the member to assist in removing the deposited material from the member, and then forming the pulpous material on the core to constitute a coating thereon conforming with the shape of the core.
36. In a machine for coating a core in strand form with pulp, a receptacle for holding a supply of fluid containing pulpous material, a member rotating therein and having a plurality of compartments in its periphery, a foraminous covering for each compartment, means for positioning the core to be coated adjacent said foraminous covering, means for producing suction in the compartments within the fluid to deposit pulp upon the foraminous coverings, means for producing suction in the compartments after they emerge from the fluid to remove moisture from the deposited pulp for forming a fibrous sheet, means for producing pressure in a compartment for assisting in removing the deposited pulp from the member, means for removing the core and pulpous material from the member, and means for forming the pulpous material on the core to constitute a coating on the core conforming with the shape of the core.
37. In a machine for coating a core in strand form with pulp, a member having a plurality of individual compartments in its periphery covered by foraminous material, a receptacle for holding a supply of fluid containing pulpous material, means for rotating the member through the fluid, means co-operating with the compartments in contact with the fluid to deposit pulpous material from the fluid upon the associated foraminous material, means for positioning the core to be coated adjacent the foraminous material, means co-operating with the compartments without the fluid to maintain the deposited pulp in contact with the member, means co-operating with an additional compartment, also out of contact with the fluid, to release the deposited material from engagement with the member, means for removing the core and pulpous material from the member and means for forming the pulpous material on the core to constitute a coating thereon conforming with the shape of the core.

a coating thereon conforming with the shape of the core.

38. A machine for coating a core in strand form with pulp, a member having a plurality of individual compartments in its periphery covered by foraminous material, a receptacle for holding a supply of fluid containing pulpos material, means for moving the member so that the compartments pass through the fluid in sequential order, means for positioning the core to be coated adjacent the foraminous material, means co-operating with the compartments in engagement with the fluid to deposit pulpos material upon the foraminous coverings of such compartments, means co-operating with the compartments which have passed through and become disengaged from the fluid to prevent fluid therein from flowing against and releasing the material from the foraminous member and to remove moisture from the pulpos material to form a sheet, means for removing the core and pulpos material from the foraminous member and means for forming the pulpos material on the core to constitute a coating thereon conforming with the shape of the core.

39. A method of coating a core in strand form with pulp, which consists in depositing pulpos material on a foraminous member, causing contact between said core and the pulpos material on the foraminous member, removing the core and the pulpos material from said foraminous member, and then forming said material on the core to constitute a homogeneous coating thereon having a substantially circular outer surface.

40. A method of coating a core in strand form with pulp, which consists in depositing pulpos material on a foraminous member, causing contact between said core and the pulpos material on the foraminous member, simultaneously removing the core and pulpos material from said foraminous member, and then forming said material on the core to constitute a homogeneous coating thereon having a curved outer surface.

41. A method of coating a core in strand form with pulp, which consists in depositing a ribbon of pulpos material on a foraminous member, causing contact between said core and the pulpos ribbon on the foraminous member, removing the core and pulpos ribbon from said foraminous member and then forming the material on the core to constitute a coating conforming with the shape of the core.

42. A method of coating a core in strand form with pulp, which consists in depositing a continuous ribbon of pulpos material on a foraminous member causing contact between said core and the continuous pulpos ribbon on the foraminous member, removing the core and continuous pulpos ribbon from said foraminous member and then

forming the material on the core to constitute a coating conforming with the shape of the core.

43. A method of coating a core in strand form with pulp, which consists in depositing wet pulpos material on a foraminous member, positioning the core adjacent said deposited material, depositing additional wet pulpos material on the core and on said foraminous member, removing the core and all of the pulpos material from the foraminous member and simultaneously removing some of the moisture from said material and then forming the material on the core to constitute a coating thereon conforming with the shape of the core.

44. A method of coating a core in strand form with pulp, which consists in depositing wet pulpos material on a foraminous member, positioning the core adjacent said deposited material, depositing additional wet pulpos material on the core and on said foraminous member, removing the core and all of the pulpos material from the foraminous member and simultaneously removing part of the moisture from said material, forming the material on the core to constitute a coating thereon conforming with the shape of the core, and then removing substantially all of the moisture from said material.

45. A method of coating a core in strand form with pulp, which consists in depositing wet pulpos material on a foraminous member, positioning the core adjacent said deposited material, depositing additional wet pulpos material on the core and on the foraminous member, removing the core and all of said pulpos material from the foraminous member and simultaneously removing some of the moisture therefrom, removing additional moisture from said pulpos material forming said material around said core to constitute a homogeneous coating therefor conforming with the shape of the core, and then removing substantially all of the moisture from said coating.

46. A method of coating a core in strand form with pulp, which consists in depositing a ribbon of wet pulpos material on a foraminous member, placing the core adjacent said deposited material, depositing additional wet pulpos material on the core and on said deposited ribbon, removing the core and said ribbon from the foraminous member and simultaneously removing some of the moisture from said ribbon and then forming the material on the core to constitute a coating thereon conforming with the shape of the core.

47. A method of coating a core with pulp, which consists of depositing a ribbon of wet pulpos material on a foraminous member, placing the core adjacent said deposited material, depositing additional wet pulpos

material on the core and on said ribbon, removing the core and said ribbon from the foraminous member and simultaneously removing some of the moisture from said 5 ribbon, and then wrapping said ribbon around the core to constitute a homogenous coating therefor.

48. A method of coating a core with pulp, which consists in depositing a ribbon of 10 wet pulpos material on a foraminous member, placing the core adjacent to said deposited material, depositing additional wet pulp-

ous material on the core and on said ribbon, removing the core and said ribbon from the foraminous member and simultaneously removing some of the moisture from said 15 ribbon, wrapping said ribbon around the core to constitute a homogeneous coating therefor, and then removing substantially all of the moisture from said coating.

In witness whereof, we hereunto subscribe our names this 16th day of Feb. A. D., 1923.

HOWARD GEORGE WALKER.
ALBERT THOMAS MARCH.
